UNITED STATES PATENT OFFICE

2,084,493

CONTAINER-DUSTER FOR INSECTICIDE
POWDEREdward B. Hunn, Cranford, N. J., assignor to
Stanco Inc.

Application March 1, 1935, Serial No. 8,794

3 Claims. (Cl. 43—147)

This invention relates to improvements in insecticide powder containers and dusters, and relates particularly to improvements in insecticide powder containers which are also used as dusters.

The hand operated dusters which are now marketed for applying insecticide and fungicidal powders are of the same general design consisting of a powder container at the head end of the duster in back of which is the usual type of cylinder and piston or plunger which is operated by means of a handle. The cheapest of these dusters is made up of a single long cylinder of metal or cardboard, the front end of the cylinder being divided off into a separate compartment to hold the powder; the rear portion of the cylinder contains a movable plunger or piston which is used to force air through the powder compartment giving a cloud of dust. A number of types of air valves (inserted in the wall between the dust compartment and the piston compartment) and outlet nozzles (at the head end of the duster) are in common usage. The design of these governs largely the efficiency of mixing of air and powder, giving a more or less uniform distribution of dust from the nozzle.

These dusters operate very efficiently, the main disadvantage being that the cost of the duster is high considering the amount of powder which it will hold. Ordinarily, the powder compartment occupies only 30 to 40% of the total volume of the duster and a duster which will hold a pound of powder, which amount is desirable from a practical standpoint (because of the nuisance and delay due to necessary frequent refilling when smaller capacity dusters are used), not only becomes unwieldy in size but excessive in cost.

An object of this invention is to provide a commercial container for insecticide powder which is also used as a duster to discharge a cloud of finely divided insecticide powder from an outlet of the container.

Another object is to provide an insecticide powder container in which the body of the duster, which contains insecticide powder, is used as the piston or plunger of the pump.

Another object of this invention is to provide a container-duster in which practically the entire space occupied by the container duster is filled with powder. This makes it possible, for a given quantity of powder, to have the smallest possible duster, which is advantageous from the standpoint of cost of construction and cost of packing and shipping.

Other objects and advantages will be apparent from the following description considered in con-

junction with the accompanying drawing, in which

Fig. 1 is a perspective side and front end view of the container-duster.

Fig. 2 is a longitudinal vertical section of the container-duster.

Fig. 3 is a longitudinal vertical section of the container.

Fig. 4 is a longitudinal vertical section of the outer sleeve that fits over the head end of the container.

Fig. 5 is a longitudinal vertical section of the outer sliding sleeve that fits over the rear end of the container.

Fig. 6 is a sectional view taken on the line 2—2 of Fig. 2.

Fig. 7 is a sectional view taken on the line 3—3 of Fig. 2, and

Fig. 8 is a sectional view taken on the line 4—4 of Fig. 5.

Referring to the drawing, numeral 1 designates a container which is cylindrical in form, with an open end 2 and a closed end 3. The container 1 is constructed of a fibrous material preferably cardboard. The closure at 3 is provided with an inlet opening 4 to which is attached a flexible tube 5 formed for example of rubber. The flexible tube 5 is provided with a heavy plug 6 on the end and a slit 7 so that air may only pass in one direction inwardly into the container 1. The heavy plug 6 serves to maintain the slit 7 in the lowest portion of the container 1.

An outer close fitting cylindrical sleeve 8, with an open end 9 and a closed end 10 is provided which is used to cover the open end 2 of the container 1. This outer sleeve 8 is held by friction when it is forced over to enclose a portion of the container 1. A small quantity of adhesive, such as glue, may be used to hold sleeve 8 and container 1 in position. A T-tube 11 provided with an outlet nozzle 12 serves as an outlet through the closed end 10. Outlet nozzle 12 is closed with a slip or screw cap 13. The ends 14 of the cross tube 11a of the T-tube are compressed or flattened, by which means the quantity of the powder expelled may be regulated.

A slide cylinder cover 15 with an open end 16 and a closed end 17 is provided to enclose the closed end 3 and a portion of container 1. The cover 15 is provided with inlet valves or openings 18 in the closed end 17 of cover 15. These valves or openings 18 are covered from the inside with a flat fibrous material, such as paper, held in position by rivet or bolt 19 to form a type of a "flap" valve, which will allow air to pass freely

into cylinder cover 15 when suction is exerted from the inside but will not allow any air to escape outwardly through this valve when the air inside is placed under pressure.

5 In the assembly of the container-duster, the container 1 is first slid into the slideable cylinder cover 15 as far as it will go so that cover 15 is filled with container 1. The container is then filled with the finely powdered insecticidal material and the open end slid into outer close-fitting sleeve 8. The outlet 12 is covered with the cap 13 and the container-duster may be stored or shipped until it is used.

10 When it is to be used, cap 13 is removed and the cover 8 together with container 1 is firmly held while cover 15 is moved or slid alternately backwards and forwards to force air through container 1 and air and dust through outlet 12.

15 The foregoing description is merely illustrative and various changes and alternative arrangements may be made within the scope of the appended claims in which it is my intention to claim all inherent novelty in the invention as broadly as the prior art permits.

20 25 I claim:

1. In an apparatus for storing and spraying powdered material, the combination of a fibrous cylindrical container for powdered material, an outer telescoping cover member having a sliding fit over the cylindrical container and adapted to be reciprocated thereover, the cylindrical container being provided on one end with a closure having a narrow constricted outlet, and the other end of the cylindrical container having a closure with a narrow constricted inlet, a flexible tube mounted in the inlet, said tube being weighted to maintain the inner end thereof in the lowest portion of the container and slitted to allow air to pass into the cylindrical container through the powdered material therein, and a closure on one end of the outer telescoping cover member with air inlets adapted to pass air into the outer telescoping cover member, the walls of the cylindrical container and the outer telescoping cover member being adapted to serve as an air seal.

2. In an apparatus for storing and spraying powdered material, the combination of a cylindrical container for powdered material, an outer telescoping cover member having a sliding fit over the cylindrical container and adapted to be reciprocated thereover, the cylindrical container being provided on one end with a closure having a narrow constricted outlet, said narrow constricted outlet being arranged on the inside of the cylindrical container with a T-member having 10 partially constricted openings at the ends of the cross member of the T-member, the other end of the cylindrical container having a closure with a narrow constricted inlet, a weighted flexible tube mounted in the inlet, said narrow constricted 15 inlet being slotted to allow air to pass into the cylindrical container, and a closure on one end of the outer telescoping cover member having air inlets adapted to allow air to pass into the outer telescoping cover member, the walls of the cylindrical container and the outer telescoping cover member being adapted to serve as an air seal.

20 25 3. In an apparatus for storing and spraying powdered material, the combination of a cylindrical container for powdered material having a closure for one end comprising a disc secured to the walls of the container and having a centrally disposed opening therein adapted to receive a flexible elongated tubular member extending into the container, a lateral slit in said member 30 adjacent the inner end forming a self-closing opening therein, a weighted plug for the inner end of the tubular member adapted to depress said end whereby the slit will be submerged in the contents of the container at all times, a cylindrical compression member telescopically associated with the container forming a compression chamber communicating with the container through said elongated tubular member, and a friction fitted cylindrical sleeve telescopically disposed over the other end of the container, said sleeve having a closed end with an outlet nozzle 35 40 45 therein.

EDWARD B. HUNN.
